UNITED STATES PATENT OFFICE

152,949

DESIGN FOR A COFFEE TABLE

Charles Eames, West Los Angeles, Calif., assignor to Evans Products Company, Detroit, Mich., a corporation of Delaware

Application March 27, 1947, Serial No. 137,931

Term of patent 14 years

(Cl. D33—14)

To all whom it may concern:

Be it known that I, Charles Eames, a citizen of the United States, residing at West Los Angeles, in the county of Los Angeles and State of California, have invented a new, original, and ornamental Design for Coffee Table, of which the following is a specification, reference being had to the accompanying drawings, forming a part thereof.

I claim:

The ornamental design for a coffee table, as shown.

CHARLES EAMES.
